ATTORNEY

UNITED STATES PATENT OFFICE.

ELIZABETH DALTON, OF JUNCTION CITY, KANSAS.

BIB.

1,284,252.

Specification of Letters Patent. Patented Nov. 12, 1918.

Application filed March 22, 1917. Serial No. 156,719.

To all whom it may concern:

Be it known that I, ELIZABETH DALTON, a citizen of the United States, residing at Junction City, in the county of Geary and State of Kansas, have invented certain new and useful Improvements in Bibs, of which the following is a specification.

This invention relates to a bib for infants and the principal object of the invention is to provide a device of this character which will prevent the infant from dropping his food into his lap or onto the floor while in his chair.

Another object of this invention is to form a pocket in the bib, whereby such articles of food as are dropped by the baby will be caught and held in the pocket.

Another object of the invention is to provide means for attaching part of the bib to the chair to hold the pocket open.

Another object of my invention is to provide a device of this character which is simple and durable in construction, reliable and efficient in operation and one which can be manufactured and placed upon the market at a minimum cost.

In describing my invention in detail, reference will be had to the accompanying drawings, wherein like characters denote like or corresponding parts throughout the several views, and in which:

Figure 1 shows the invention in elevation.

Fig. 2 is a section on line 2—2, Fig. 1.

Fig. 3 is a section on line 3—3, Fig. 2.

As shown in these drawings, the bib has a substantially flat body 1 provided with the ordinary strings 2 for securing the same to the infant and at its lower end the bib is provided with a pocket 3 formed in any desirable manner. The material forming the pocket is provided with eyelets 4 along the upper edge adapted to engage with buttons 5 on the inner edge of the high chair table, such buttons being formed in any desirable manner, those shown consisting of furniture tacks driven into the table.

Thus it will be seen that the pocket is held open by the buttons, so that any food that may be dropped by the baby will be caught in the pocket and thus prevented from dropping into the baby's lap or onto the floor.

The bib may be made of any suitable material, such as a rubber, oil cloth or the like. Further, the bib may be of any shape desired.

While I have shown the invention in use with a high chair, I do not wish to be limited to this combination, as of course the bib could be used with an ordinary chair having a bar in front to hold the baby in the chair and this bar could carry the buttons for holding the pocket open.

Again, the chair could be moved close to the edge of the table and the buttons applied to this so as to hold the pocket open.

It is thought from the foregoing that the advantages and novel features of my invention will be readily apparent.

I desire it to be understood that I may make slight changes in the construction and the arrangement and combination of the several parts, provided such changes fall within the scope of the appended claim.

I claim as my invention:

The herein described bib comprising one piece of material forming a flat body, fastening means at its upper end, a pocket comprising a separate piece of material extending across the lower end of the body with its extremities coincident with and attached to the edges of the same and its upper edge bowed normally outward therefrom, and fastening devices along the upper edge of said pocket adapted to co-act with others along the edge of the table of a high chair to hold the pocket to the table and open when in use.

In testimony whereof I affix my signature in presence of two witnesses.

ELIZABETH DALTON.
